TURBINE BLADING

James L. Ray, Wauwatosa, Wis., assignor to Allis-Chalmers Manufacturing Company, Milwaukee, Wis., a corporation of Delaware

Application February 23, 1939, Serial No. 257,927

16 Claims. (Cl. 253—77)

This invention relates to turbine blading and more particularly to the construction and the manner of mounting the impulse blades of elastic fluid turbines.

5 The design of efficient impulse blading for high pressure, high temperature turbines of the superimposed or topping unit type necessitates in most instances the use of opposed concave convex fluid passage defining surfaces disposed in nested or in 10 partially nested relationship to form a circumferential blade row. The known manner of construction a circumferential blade row in which spaced concave convex fluid passage defining surfaces are disposed in nested or in partially 15 nested relationship embodies the use of a circumferential extending blade retaining groove and blades each having a root portion and a body portion including oppositely disposed concave convex surfaces. The retaining groove or 20 grooves, depending upon the number of circumferential blade rows employed, are each enlarged usually at only one point to permit the insertion of the blade root into the groove. The blades are inserted one at a time and are moved 25 circumferentially of the groove from the point of insertion and into spaced nested relationship until the groove is completely filled. The last blade to be inserted is secured in place by suitable wedging and locking members.

30 Experience in designing turbines to operate with steam at extreme high pressures and temperatures and at high rotative speeds shows that the intermittent application of the driving fluid in partial admission wheels, which produces forces 35 that may amount to many hundreds of pounds per blade, necessitates the use of blades of relatively great width for safe operation. When blades of great width are employed under conditions of high relative speed and high temperature, the use of a circumferential retaining groove 40 becomes impractical because of the great width of the supporting rims at the sides of the blades and also because of the great difficulty of providing a suitable closing or locking device for 45 holding the last blade in place. There is no known manner of inserting and securing the last blade in a circumferential groove in which blades are spaced to provide highly efficient fluid 50 passages under conditions of maximum capacity and maximum temperature without materially increasing the stresses set up in the region of the last blade.

Consequently, in the known blade assemblies of the type under consideration of the removal 55 and replacement of a defective blade is extreme-

ly expensive as all of the blades disposed between the defective blade and the enlarged portion of the retaining groove must first be removed. Moreover, the enlargement of a circumferentially extending blade retaining groove, to permit the insertion of the blades, greatly weakens the portions of the generally horizontal blade retaining surfaces in the region of the enlargement, and the bending moments set up by the intermittent application of the driving fluid render the obtainment of a stable structure highly impractical. Furthermore, the formation of a sealed fluid confining passage necessitates the use of an integral shroud structure and the welding together of the abutting edges of adjacent shrouds which in turn hinders the ready removal and replacement of defective blades. In addition, the dimensions of the fluid confining passages will vary with the blade pitch and degree of accuracy with which the blades are assembled.

5 Therefore, it is an object of this invention to provide an improved and novel impulse blade construction for elastic fluid turbines.

Another object of this invention is to provide a novel and improved impulse blade construction 25 presenting a fluid confining passage of fixed dimensions.

Another object of this invention is to provide an improved and novel impulse blade construction 30 presenting a sealed fluid confining passage.

Another object of this invention is to provide a novel and improved impulse blade construction 35 embodying spaced concave convex passage defining surfaces disposed in nested or in partially nested relationship.

Still another object of this invention is to provide a novel and improved impulse blade assembly 40 permitting the separate insertion and removal of any individual blade from a circumferential blade row in which spaced concave convex fluid passage defining surfaces are disposed 45 in nested relationship.

The invention accordingly consists of the various features of construction, combination of elements, and arrangement of parts, as more fully set forth in the appended claims and in the detailed description, in which:

Fig. 1 is a perspective view of two blade forming structures embodying the invention disposed in their proper cooperative relationship;

Fig. 2 is a partial sectional view illustrating a turbine spindle embodying the invention and the coating portion of the turbine casing;

Fig. 3 is an elevational view of the right hand side of the smaller blade structure shown in 55

Fig. 2 with the adjacent portion of the spindle shown in section;

Fig. 4 is an elevational view of the left hand side of the smaller blade structure shown in Fig. 2;

Fig. 5 is a sectional view of a blade forming structure taken on line V—V of Fig. 2;

Fig. 6 is a top plan view of the smaller blade structure shown in Fig. 2; and

Fig. 7 is a sectional view taken on line VII—VII of Fig. 2.

The blade construction illustrated in the drawing comprises adjoining blade forming structures each having a root portion 1, and a body portion 2, which portions together constitute the supporting portion of a blade forming structure, and means designated generally by the numeral 3 extending from the body portion 2 and defining a fluid confining passage or channel 4. The passage defining means 3 includes a first member 6 having a concave side surface 7 and a second member 8 spaced from said first member and having a convex side surface 9 disposed in partially nested relationship with respect to the concave surface 7. The remaining side surfaces of the first member 6 include oppositely disposed plane surfaces 11, each of which is approximately tangential with respect to the adjacent edge of the concave surface 7, and a third plane surface 12 oppositely disposed with respect to the concave surface 7. The second member 8 also has a plane side surface 13 oppositely disposed with respect to the convex surface 9 and with respect to the plane surface 12 of the first member 6. The first member 6 has a top portion 14 extending beyond each of said oppositely disposed side surfaces 11 and in overlying relationship with respect to the body portion 2. A sealing member 16 conforming with the configuration of the fluid passage 4 when viewed in plan is disposed between the first and second members 6 and 8 and coacts with said first and second members and with the top portion 14, and defines with said first and second members and body portion a sealed fluid confining passage. The member 16 may be secured in place in any desired manner such as by welding.

The oppositely disposed plane side surfaces 11 of the first member 6, in addition to being approximately tangential with respect to the adjacent edge of the concave side surface 7, are substantially tangential with respect to the convex surface 9 at the adjacent edge of the fluid passage or channel 4 of the next adjacent blade structure. The body portion 2 and the top portion 14, including the sealing member 16, have oppositely disposed side surfaces 11 and 18, respectively, disposed in the plane of the similarly disposed plane side surfaces 12 and 13 of the first and second members, respectively. The oppositely disposed plane side surfaces 12 and 13 may lie in planes having a common axis coincident with the axis of the turbine spindle on which the blades are adapted to be mounted. The abutting surfaces of adjacent blade forming structures are adapted for sliding engagement and dimensioned for coincident contact.

The top surface 19 of the body portion 2, which extends beyond the plane side surfaces 11, forms an approximate continuation of the surface defining the bottom of the fluid passage or channel 4 of the next adjacent blade structure. The body portion 2 is provided with a projection extending laterally with respect to the blade row and presenting a plane sealing surface 20, as shown in

Figs. 1, 2, and 6. The under surface 21 of the top portion forms a continuation of the under surface of the sealing member 16 of the next adjacent blade structure. The construction is such that when the blade forming structures are assembled in abutting relationship to form a circumferential blade row, as best shown in Fig. 1, the plane side surfaces 12, 17, and 18 of one blade forming structure are in substantial coincidence with the plane side surfaces 13, 17, and 18 of the next adjacent blade forming structure, the plane side surfaces 11 on one blade member form with the convex side surface 9 on the next adjacent blade a continuous fluid directing surface, and the top surface 19 of the body portion 2 and the under surface 21 of the top portion 14 and of the sealing member 16 form with the similar surfaces of the next adjacent blade forming structure continuous fluid confining and directing surfaces.

Stated differently, the illustrated blade forming structures each has oppositely disposed side surfaces arranged for sliding engagement and coincident contact with the like surfaces of adjacent structures and each structure comprises a supporting portion having oppositely disposed sides and a complementary blade forming member extending from said supporting portion adjacent each of said sides and said members each including a side surface defining the major portion of the said oppositely disposed surfaces on said structure. In this connection it should be noted that each structure includes two blade forming members each of which is the complement of that portion of a blade defined by the other of the said two members and that each member on one structure is also the complement of that portion of a blade defined by the adjacent member on an adjoining structure.

In order to secure the best flow efficiency, the width of the fluid confining passage 4, as best shown in Figs. 6 and 7, gradually decreases toward the outlet end while the height of the passage, as shown in Fig. 2, increases toward the outlet end. The central portions of the opposed concave convex passage defining surfaces 7 and 9 are, best shown in Figs. 4 and 5, substantially parallel to the plane side surfaces 12 and 13, respectively. The fluid confining passage or channel 4 may be machined in a generally rectangular metal block of suitable dimensions by means of an ordinary hollow, cylindrical milling cutter. The hollow cylindrical cutter is mounted for exact vertical movement, and the block is rigidly held by any suitable means in a position slightly inclined with respect to the vertical axis of the cylindrical cutter and so that the axis of the cutter is in coincidence with the center of curvature 22, as seen in Figs. 6 and 7. The convex side surface 9 can then be machined by a single cutting operation. The block is then tilted in the opposite direction, and shifted with respect to the axis of the cylindrical cutter so that the axis of the cutter is in coincidence with the center of curvature 23, shown in Figs. 6 and 7. The concave surface 7 can then be machined by a single cutting operation. Consequently, only two machining operations are necessary to form the fluid passage or channel 4. The same result can obviously be accomplished by securing the block in an exact vertical position and by tilting and shifting the hollow cylindrical cutter in the same respects as specified in the example in which the block was tilted and shifted and the cutter remained in an exact vertical position. The plane

side surfaces, the top portion, and the slotted root portion are machined in the usual manner.

Fig. 2 illustrates a turbine spindle 24 having two axially spaced circumferential blade rows 25 between which is cooperatively disposed a circumferential row of stationary blades 26 which are mounted in the turbine casing 27 in a known manner. The casing 27 also includes one or more groups of admission nozzle passages 28 of which only one nozzle passage is shown. The spindle 24 is provided with a circumferential row of spaced, axially extending blade retaining grooves 29. The cross-sectional configuration of the grooves 29 conforms with the cross-sectional configuration of the slotted blade root 1, and the blade structures are inserted into the grooves by movement in a lateral direction with respect to the circumferential blade row. The grooves 29 may be finished by a single broaching operation, and may be of any desired length in order to form a plurality of circumferentially extending blade rows.

The axial spacing of the blade forming structures is accomplished by means of a slotted spacing block 31 disposed between the blade forming structures in each axial groove, and in order to facilitate removal of the blade structures, and to reduce machining costs, the space 32, lying above the spacing block 31 and between the circumferential blade rows, may be provided by cutting a circumferentially extending groove having a cross-sectional configuration conforming with the plane space 32, as shown in Fig. 2, and similarly located with respect to the end of the spindle before cutting the axially extending blade retaining grooves 29. The spindle 24 is provided with circumferential retaining grooves 33, and the adjacent bottom edges of the blade forming structures are cut away to form a continuation of the groove throughout the axially grooved portions of the spindle when the blade structures are in place. Any suitable means may be inserted in the grooves 33 for preventing movement of the blade structures in a lateral direction with respect to the blade row. The means illustrated comprises a retaining ring 34, which is generally made in segments, and is inserted in a known manner.

The blades of the stationary blade row 26 are provided with sealing projections 36, which coat with the sealing surfaces 20 of the moving blades to prevent the passage of the driving fluid around the ends of the stationary blades. The moving blades are generally provided with means adapted to coat with sealing surfaces on the casing 27 for a similar purpose. However, the means for sealing the spaces adjacent the ends of the moving blades have not been disclosed as they are not deemed essential for an understanding of the invention. In addition, it should be borne in mind that the disclosed blade structure retaining means, the slotted root and groove, are merely illustrative, as the only requisite is that the spindle be provided with a circumferential row of spaced blade retaining means into which a part of the supporting portion of a blade forming structure is inserted by moving the blade structure in a lateral direction with respect to the circumferential row. A retaining means of this nature, in combination with the disclosed blade structure, permits the separate insertion and removal of any individual blade structure from a circumferential row of blades in which the fluid confining passage 75 or channel is defined by spaced concave convex

surfaces disposed in nested or in partially nested relationship.

The invention is obviously applicable to spindles employing only a single circumferential blade row, and in this connection it should be borne in mind that the disclosed relative dimensions and arrangement of parts are merely illustrative and may be materially altered without departing from the spirit of the invention. Therefore, it should be understood that it is not desired to limit the invention to the exact details of construction herein shown and described, for various modifications within the scope of the claims may occur to persons skilled in the art.

1. A turbine blade forming structure comprising a supporting portion and spaced complementary blade forming members extending from said supporting portion and presenting opposed surfaces defining therebetween a channel for the passage of the driving fluid, said members each constituting a portion of a complete blade and each having a side surface oppositely disposed with respect to said opposed passage defining surfaces and arranged for sliding engagement and coincident contact with the side surface of a complementary blade forming member on an adjacent blade structure so that when the blade structures are arranged to form a blade row, the side surfaces of the blade forming members on adjacent structures will be in substantial coincidence and said members on adjacent structures will coat and form blades having contiguous fluid directing surfaces.

2. A turbine blade forming structure comprising a supporting portion and spaced members extending from said supporting portion and presenting opposed surfaces, one of which is concave and the other convex, defining therebetween a channel for the passage of the driving fluid, said members each having a plane surface oppositely disposed with respect to said opposed surfaces and dimensioned for coincident contact with the abutting surface of a member on an adjacent blade structure, and the member embodying said concave surface also having oppositely disposed plane side surfaces each of which is substantially tangential with respect to the convex surface at the adjacent end of the channel of the next adjacent blade structure.

3. A turbine blade forming structure comprising a supporting portion, spaced members extending from said supporting portion and presenting opposed surfaces, one of which is concave and the other convex, defining therebetween a channel for the passage of the driving fluid, said members each having a plane surface oppositely disposed with respect to said opposed surfaces and dimensioned for coincident contact with the abutting surface of a member on an adjacent blade structure, and the member embodying said concave surface also having oppositely disposed plane side surfaces each of which is substantially tangential with respect to the convex surface at the adjacent end of the channel of the next adjacent blade structure, and means coacting with portions of said spaced members remote from said supporting portion and defining with said supporting portion and spaced members a sealed fluid confining passage.

4. A turbine blade forming structure comprising a supporting portion, spaced members extending from said supporting portion and presenting opposed surfaces, one of which is concave and the other convex, defining therebe-

tween a channel for the passage of the driving fluid, said members each having a plane surface oppositely disposed with respect to said opposed surfaces and dimensioned for coincident contact 5 with the abutting surface of a member on an adjacent blade structure, and the member embodying said concave surface also having oppositely disposed plane side surfaces each of which is substantially tangential with respect to the 10 convex surface at the adjacent end of the channel of the next adjacent blade structure, and a top portion extending beyond each of said plane side surfaces and overlying said supporting portion, and means coacting with said spaced members and with said top portion and defining with said supporting portion and spaced members a sealed fluid confining passage.

5. A turbine blade forming structure comprising a supporting portion, a first means extending 20 from said supporting portion and having sides including a concave surface, oppositely disposed plane surfaces each of which is approximately tangential with respect to the adjacent edge of said concave surface and another plane 25 surface oppositely disposed with respect to said concave surface, and a second means extending from said supporting portion in spaced and partially nested relationship with respect to said first means and having sides including a convex 30 surface oppositely disposed with respect to said concave surface and a plane surface oppositely disposed with respect to said convex surface and with respect to said another plane surface on said first means, said another surface and the 35 plane surface on said second means being adapted for sliding engagement and dimensioned for coincident contact with the abutting surfaces of members on adjacent blade structures.

6. A turbine blade forming structure comprising 40 a supporting portion, a first means extending from said supporting portion and having sides including a concave surface, oppositely disposed plane surfaces each of which is approximately tangential with respect to the adjacent edge of 45 said concave surface and another plane surface oppositely disposed with respect to said concave surface, a second means extending from said supporting portion in spaced and partially nested relationship with respect to said first means and 50 having sides including a convex surface oppositely disposed with respect to said concave surface and a plane surface oppositely disposed with respect to said convex surface and with respect to said another plane surface on said first means, said first means also having a top portion extending beyond said oppositely disposed plane surfaces and overlying said supporting portion, and said another surface and the plane surface on said second means being adapted for sliding 55 engagement and dimensioned for coincident contact with the abutting surfaces on adjacent blade structures, and means coacting with said first and second means and with said extending top portion and defining with said extending top portion, with said first and second means and with said supporting portion a sealed fluid confining passage.

7. A turbine blade assembly comprising a spindle having a circumferential row of spaced blade 70 retaining means into which part of the supporting portion of a blade structure is inserted by moving the blade structure in a lateral direction with respect to said row and blade structures each having a supporting portion, and coacting with said retaining means on said supporting

portion forming spaced complementary blade forming members each constituting a portion of a complete blade and having oppositely disposed side surfaces arranged for sliding engagement and dimensioned for coincident contact with the side surfaces of members on adjacent blade structures so that said members on adjacent structures coat and form blades each having contiguous fluid directing surfaces. 5

8. A turbine blade assembly comprising a spindle having a circumferential row of spaced blade retaining means into which part of the supporting portion of a blade structure is inserted by moving the blade structure in a lateral direction with respect to said row and blade structures 10 each having a supporting portion, spaced complementary blade forming members each constituting a portion of a complete blade extending from said supporting portion and presenting opposed passage defining surfaces and having side surfaces oppositely disposed with respect to one another and with respect to said passage defining surfaces, said side surfaces being adapted for sliding engagement and dimensioned for coincident contact with the side surfaces of members or adjacent blade structures so that said members on adjacent blade structures coat and form blades having contiguous fluid passage directing surfaces, and means coacting with portions of said spaced members remote from said supporting portion and defining with said spaced members and supporting portion a sealed fluid confining passage. 20

9. A moving blade assembly for elastic fluid turbines permitting the separate insertion and removal of any individual blade structure from a row of blades in which spaced concave convex fluid passage defining surfaces are disposed in nested or in partially nested relationship comprising a spindle having a circumferential row of spaced, axially extending grooves and blade structures each having a supporting portion including a part slideable into and out of said grooves by movement in a direction generally parallel with respect to the spindle axis, and means on said supporting portion forming complementary blade members each constituting a portion of a complete blade and having a side surface arranged for sliding engagement and coincident contact with the side surface of a member on an adjacent blade structure and a fluid directing surface adjoining said side surface and so arranged that said members on adjacent structures coat and form blades having contiguous fluid directing surfaces. 30

10. A turbine blade assembly comprising a spindle having a circumferential row of spaced blade retaining means into which the retaining portion of a blade structure is inserted by moving the blade structure in a lateral direction with respect to said row and blade structures 40 each having a supporting portion, spaced members extending from said supporting portion and presenting opposed surfaces, one of which is concave and the other convex, defining therebetween a channel for the passage of the driving fluid, said members each having a side surface oppositely disposed with respect to said opposed surfaces and dimensioned for coincident contact with the abutting surfaces of members on adjacent blade structures and the member embodying said concave surface also having oppositely disposed plane side surfaces each of which is substantially tangential with respect to the convex surface at the adjacent end of the channel of the next adjacent blade structure so that said mem- 50

- bers on adjacent structures coact and form blades having contiguous concave-convex fluid passage directing surfaces, a top portion extending beyond each of said plane side surfaces and overlying said supporting portion, and means coacting with said spaced members and with said top portions and defining with said supporting portion and spaced members a sealed fluid confining passage.
11. A turbine blade assembly comprising a spindle having a circumferential row of spaced blade retaining means into which the retaining portion of a blade structure is inserted by moving the blade structure in a lateral direction with respect to said row and blade structures each having a supporting portion, spaced members extending from said supporting portion and presenting opposed surfaces, one of which is concave and the other convex, defining therebetween a channel for the passage of the driving fluid, said members each having a side surface oppositely disposed with respect to said opposed surfaces and dimensioned for coincident contact with the side surfaces of members on adjacent blade structures and the member embodying said concave surface also having oppositely disposed plane side surfaces each of which is substantially tangential with respect to the convex surface at the adjacent end of the channel of the next adjacent blade structure so that the members on adjacent structures coact and form blades each having contiguous concave-convex fluid passage directing surfaces, a top portion extending beyond each of said plane side surfaces and overlying said supporting portion, and means coacting with said spaced members and with said top portions and defining with said supporting portion and spaced members a sealed fluid confining passage.
12. A turbine blade assembly comprising a spindle having a circumferential row of spaced blade retaining means into which part of the supporting portion of a blade structure is inserted by moving the blade structure in a lateral direction with respect to said row and blade structures, each having a supporting portion, spaced members extending from said supporting portion and presenting opposed surfaces, one of which is concave and the other convex, defining therebetween a channel for the passage of the driving fluid, said members each having a plane side surface oppositely disposed with respect to said opposed surfaces and dimensioned for coincident contact with the side surfaces of members on adjacent blade structures and the member embodying said concave surface also having oppositely disposed plane side surfaces each of which is substantially tangential with respect to the convex surface at the adjacent end of the channel of the next adjacent blade structure so that the members on adjacent structures coact and form blades each having contiguous concave-
- convex fluid directing surfaces, a top portion extending beyond each of said oppositely disposed plane side surfaces and overlying said supporting portion, and means coacting with said spaced members and with said top portions and defining with said spaced member and supporting portion a sealed fluid confining passage.
13. A turbine blade forming structure comprising a supporting portion and two complementary blade forming members extending from said supporting portion in spaced relation, each of said members constituting a portion of a complete blade and each of said members being the complement of that portion of a complete blade defined by the other of the said two members.
14. A turbine blade forming structure comprising a supporting portion and two spaced complementary blade forming members extending from said supporting portion and presenting opposed concave-convex passage defining surfaces disposed in partially nested relationship, each of said members constituting a portion of a complete blade, and each of said members being the complement of that portion of a complete blade defined by the other of the said two members.
15. A turbine blade assembly comprising adjoining structures each having a supporting portion and two blade forming members extending from said supporting portion in spaced relation, each of said members constituting a portion of a complete blade and each of said members being the complement of that portion of a complete blade defined by the adjacent member on an adjoining structure, said members each having a similarly disposed side surface arranged for sliding engagement and coincident contact with the like surface of the adjacent member on an adjoining structure, and said adjacent members on adjoining structures coacting to form blades each having contiguous fluid directing surfaces.
16. A turbine blade forming structure having oppositely disposed side surfaces arranged for sliding engagement and coincident contact with the like surfaces of adjacent structures comprising a supporting portion having oppositely disposed sides and a complementary blade forming member extending from said supporting portion adjacent each of said sides, said members being disposed in spaced relation so as to form therebetween a passage for the driving fluid, each of said members constituting a portion of a complete blade and being the complement of that portion of a complete blade defined by the other of the said two members, and each of said members including a side surface which forms a continuation of the adjacent one of said sides on said supporting portion and forms therewith one of the said oppositely disposed side surfaces on said structure.
